UNITED STATES PATENT OFFICE.

JOHN LEWIS MAJOR, OF LONDON, ENGLAND.

STILL.

Application filed September 4, 1923. Serial No. 660,796.

To all whom it may concern:

Be it known that I, JOHN LEWIS MAJOR, a subject of the King of Great Britain and Ireland, residing at 12 Norfolk Street, London, W.C. 2, England, have invented certain new and useful Improvements Relating to Stills, of which the following is a specification.

This invention relates to the continuous distillation or evaporation of liquids such as crude petroleum or tar, and has among its objects to facilitate evaporation and to ensure good fractionation.

The invention especially relates to the subject matter of the prior Patent No. 1,415,667 which relates to a method for the distillation of liquids, in which the liquid to be distilled is fed to the still in a number of streams through a plurality of pipes extending from the bottom up through the liquid in the still under conditions in which the liquid gradually acquires the temperature necessary for the distillation to be effected or to be commenced before overflowing from the pipes into the body of liquid in the still, the lighter vapours being disengaged on the liquid emerging from the pipes, and passed out from the still.

The invention has among its objects to improve the construction and operation of such a still and to provide simple and effective means for feeding the liquid to be distilled under pressure.

According to one part of the present invention there is provided within the vapour space in the still above the pipes through which the liquid to be distilled is fed into the still in the manner described, a horizontally disposed plate or tray against the under-face of which the lighter vapours as they are released from the pipes impinge, and this plate or tray may be provided in a number of separate parts in the same plane. Where the vapours from the still are passed through a column or dephlegmator for better fractionation, the return liquid therefrom is discharged on to the plate or tray through a sealed outlet preferably provided within the still and in position above the plate or tray. The plate or tray is advantageously provided with a steam coil or coils through which the passage of steam is controlled by a valve or valves situated outside the still and such of the return liquid as is

not vaporized on the tray flows therefrom into the body of liquid in the still.

The plate referred to may be provided as a tray with a flange or edge which may be notched to facilitate the overflow of the liquid discharged on to the tray, into the body of liquid in the still.

According to another part of the invention the pipes provided within the still and through which the liquid passes before admission to the bulk of liquid in the still, are each provided at their upper open ends with a dead weight valve adapted to close the open ends of the pipes, so that thus the liquid within the pipes is subjected to pressure before release through the valve, and such valves may be adjustable to give varying pressures. The valves advantageously take a simple form, such for example as that of a circular disc, block or ball of metal to

which is connected a concentric downwardly depending and relatively long stem of small diameter which upon the disc or block being placed in position upon the upper end of the pipe, passes into the pipe and thus maintains the valve in its position.

There may also be provided a stem above the disc, block or ball for the reception of additional weights and these may also pass through a guide or guides attached to the pipe to maintain the valve in a vertical position.

The upper end of the pipes may be of an enlarged diameter or size or of a reduced diameter or size and may be provided if desired with an outer rim or flange for the better fit of the valve. Since these pipes are under pressure, it is necessary in the case of a series of stills that pumps are employed between the stills for feeding the liquid thereto and that a pump is also provided for feeding the liquid into the first of the series should there be an insufficient head of liquid to overcome the pressure of the valves and the pressure within the still.

According to the invention, moreover, the upper ends of the plurality of pipes may be provided to discharge into a common receptacle in which pressure is maintained, and from which on a predetermined degree of pressure being attained, the liquid discharges through one or a number of outlets normally closed by a valve or valves. These valves may be maintained on their seats by their dead weight, by means of weighted

levers or by any other convenient means, permitting of the discharge of the liquid from the receptacle into the still under the pressure prevailing within the receptacle.

5 Three constructions of still provided according to the invention are illustrated in the accompanying diagrammatic drawings by way of example.

Figure 1 represents a sectional elevation 10 of a construction of still provided with a horizontally disposed plate or tray above the outlets of the pipes through which the liquid to be distilled is fed into the still.

Figure 2 is a sectional elevation of a 15 modified construction of still.

Figure 3 represents a further modification in construction of the still.

Referring to Figure 1 of the drawings the 20 still casing *a*, which may be of circular formation, is provided to receive within it a number of series of liquid inlet pipes *b* fitted upon casings *c* supported by a frame or partition *d* and connected to an inlet pipe *e* for the supply of the liquid.

25 Above the outlets of the pipes *b* there is provided in the vapour space of the still a horizontally disposed plate or tray *f* against the under face of which the lighter vapours discharged from the pipes *b* impinge.

30 An outlet for the vapour is provided at *g* and, where the vapours are passed through a column or dephlegmator, the resulting liquid may be returned by way of the pipe *h* into the tray *f*, the outlet of the pipe *h* 35 being disposed below the level of liquid maintained in the tray. The edge of the tray is advantageously notched to facilitate the discharge of the liquid therefrom and a steam heating coil *i* is also advantageously provided. The discharge of liquid from the 40 still is effected by way of the outlet pipe *j* which is open at the bottom and at the top and near the top is carried in an outlet pipe fitting as illustrated in the figures.

45 In the construction illustrated in Figure 2 the liquid is released from the pipes *b* under pressure produced by the provision of dead weight valves *k* mounted in the outlets of the pipes. Such valves may be of any convenient construction and as illustrated they 50 may comprise disc valves having stems of considerable length adapted to be received into the pipes *b*, such stems being extended upwardly for the reception of weights by 55 which the pressure exerted by the valve may be adjusted.

In the construction illustrated in Figure 3, the series of pipes *b* are provided with their respective outlet extremities connected to 60 deliver into closed receptacles *l* having outlets *m* closed by dead weight valves *n* acting after the manner of the valves *k* of the construction illustrated in Figure 2. The receptacles *l* may be connected one with the 65 other by communicating pipes *o* serving to

equalize the pressure in the several receptacles *l*.

It will be understood that any form of receptacle may be employed. The upper ends of the pipes aforesaid may for example 70 be connected to a common tubular or other fitting upon which an outlet valve or valves may be applied through which the liquid discharges in the manner described, or the upper ends of the pipes may be connected 75 to a drum mounted in the vapour space above the bulk of liquid in the still or otherwise disposed, or again instead of valves the outlet or outlets for liquid from the receptacle may be provided of small area whereby 80 the liquid may be outwardly sprayed from the receptacle under the pressure maintained therein.

It will be understood that the liquid to be distilled may be fed to the still under a 85 pressure head, or it may be fed thereto by means of a pump, and that on the liquid discharging from the plurality of pipes through which it is fed, it passes to the bulk of liquid in the still whence it is withdrawn. It will also be understood that the constructions of still described with reference to Figures 2 and 3 of the drawings may be 90 provided with trays in the manner according to the first part of the invention.

I claim:

1. In a still, in combination, a still casing, a plurality of upwardly directed feed pipes for the liquid to be distilled, said pipes being disposed within said casing and having outlets at their upper ends, a receptacle for liquid connected to the outlet of the said pipes, and means applied to said receptacle for the discharge of the liquid therefrom. 100

2. In a still, in combination, a still casing, a plurality of upwardly directed feed pipes for the liquid to be distilled, said pipes being disposed within said casing and having outlets at their upper ends, a receptacle for liquid connected to the outlet ends of the said pipes, a number of outlets to the said receptacle, and valves applied to the said outlets to determine the discharge of liquid from the receptacle. 110

3. In a still, in combination, a still casing, a plurality of upwardly directed feed pipes for the liquid to be distilled, said pipes being disposed within said casing and having outlets at their upper ends, a plurality of receptacles for liquid each connected to the outlet ends of a number of the said pipes, and means applied to the said receptacles for the restricted discharge of the liquid therefrom, substantially as described. 115

4. In a still, in combination, a still casing, a plurality of upwardly directed feed pipes for the liquid to be distilled, said pipes being disposed within said casing and having outlets at their upper ends, a plurality of receptacles for liquid each connected to the 120

outlet ends of a number of the said pipes, means applied to the said receptacles for the restricted discharge of the liquid therefrom, and a baffle device supported in said casing 5 above said feed pipes.

5. In a still, in combination, a still casing, a plurality of upwardly directed feed pipes for the liquid to be distilled, the said pipes being disposed within the said casing and 10 having outlets at their upper ends, a plu-

rality of receptacles connected to the said outlets, means applied to the said receptacles to restrict the outward flow of liquid therefrom, a shallow tray in the upper part of the still transversely disposed and immediately above the said receptacles, and means adapted to apply heat to a liquid in the said shallow tray. 15

JOHN LEWIS MAJOR.
